UNITED STATES PATENT OFFICE.

LAWRENCE OLSEN, OF INDIANAPOLIS, INDIANA.

CENTRIFUGAL DIE-CASTING MACHINE.

1,302,838.

Specification of Letters Patent.

Patented May 6, 1919.

Application filed March 2, 1918. Serial No. 220,076.

To all whom it may concern:

Be it known that I, LAWRENCE OLSEN, a citizen of the United States, residing at Indianapolis, Marion county, and State of Indiana, have invented and discovered certain new and useful Improvements in Centrifugal Die-Casting Machines, of which the following is a specification.

My invention relates to centrifugal die casting machines. The objects of the invention are to increase rapidity of production, to facilitate the closing and opening of the die members and of the separation of the casting from the dies, to effect an even and continuous distributing flow of the metal from a central point to the die chambers, to provide ejector means capable of effective operation without injury to the castings, and to enable a number of castings to be formed and separated by the same operation.

With these objects in view, my invention is embodied in preferable form in the construction and arrangement hereinafter set forth and illustrated in the accompanying drawings.

In these drawings, Figure 1 is a side view in elevation of the machine; Fig. 2, a front elevation partly in vertical section; Fig. 3, a plan view partly broken away and enlarged over the view shown in Figs. 1 and 2, and Fig. 4, an enlarged vertical section on the line 4—4 of Fig. 3.

Referring to the drawings, 1 indicates the frame work of the machine which is provided with suitable bearings 2 in which is journaled a rotatable shaft or spindle 3 adapted to be driven by suitable gearing 4 and by a tight pulley 5 driven by a belt 6 which is also adapted to be shifted to a loose pulley 7 to stop the machine. The shaft 3 is provided with a brake drum 8 adapted to be pressed against by a brake 9 controlled by a shifting lever 10, the function of which braking mechanism is to check the momentum of the shaft when the driving belt is thrown off the fixed pulley. The shaft is journaled in a vertically slideable non-rotating sleeve 11 which in turn is mounted within a split clamping sleeve 12 suitably fixed in the frame work 1. The split sleeve 12 is provided with an adjusting screw 13 operable by a lever 14 and said sleeve serves to clamp the sliding sleeve 11 in fixed position when the latter is adjusted vertically. The sleeve 11 has fixed thereto

a rack bar 15 which also serves as a vertical key for said sleeve and which is engaged by an operating pinion 16 adapted to be operated by handle members 17 whereby upon operation of the pinion the rack bar and its connected sleeve may be lowered or raised longitudinally of the axis of the shaft. Mounted in bearings 18 in the sleeve 11 is a rotatable hub sleeve 19 keyed to the shaft by means of a longitudinal key 20. The sleeve 19 carries a spider 21 and through ears 22 thereof extend bolts 23 which are fixed to a base plate 24, which may be in the form of a spider. This base plate, owing to its fixed connection to the shaft, is adapted to rotate therewith when the latter is driven, and it constitutes a carrier for the cover lifting means and ejectors.

This plate is provided with lifting rods 25 adapted to have free contact against the bottom of a cover member or head plate 26 which is adapted to close the die chambers and which may in itself constitute a complementary die carrying member. This cover 26 in the construction herein illustrated is shown as provided with a series of removable dies 27 adapted to be engaged with the cover by means of bolts 28. The cover member is provided with a central opening 29 through which the molten metal to form the casting is poured. Mounted in the chamber formed by this opening is the head 30 of a bolt 31. The head of this bolt is inclined and serves as a distributing member for the molten metal to aid in more effectively distributing the metal radially to the different gates leading to the dies. This bolt passes through a die carrying member consisting of a bed plate 32 and is then threaded into the shaft 3 whereby the die bed 32 and the shaft are rigidly connected. The cover member 26 is adapted to be removably but rigidly connected to the die bed 32 by means of bolt or bolts 33. The base plate 24 and cover 26 are conjointly movable upward relatively to the die bed 32 by the contact rods 25 to obtain the separation of the dies, and also to operate the ejectors hereinafter described, while owing to the free bearing of these rods against the cover 26, the plate 24 is movable downward independently of members 26 and 32.

Leading from the central distributing chamber 34 in the member 26 are downwardly inclined, shallow, tapering recesses 35 constituting gates for leading the molten

metal to the die chambers. A plurality of these gates are provided disposed around the central chamber and the machine is provided with a corresponding plurality of dies whereby a number of castings are formed simultaneously. These gates lead from the circular distributing chamber at such an angle to the tangent line at the junction of the edges of the gate with the circumference of the chamber as to incline the gates in the direction of the circle of rotation of the machine as indicated by the arrow in Fig. 3 and they enter the recesses 36 constituting the die chambers in the rear part of the circumferences of said chambers in the line of rotation. This construction provides a flow of the metal along a line approximating an involute curve projected from the distributing chamber to the die chamber in the general direction of the line of rotation. This construction has been found to be very effective in obtaining an even distribution of the molten metal and a uniform, unchecked flow of the same.

25 The die chambers are, of course, adapted to be varied to conform to the shape of the casting to be produced and the dies may be either provided with cores or such cores may be dispensed with in accordance with the form of such castings.

In the particular machine herein illustrated, cores 37 are shown as employed. They extend within the die chamber and are carried by bolts. In conjunction with these cores, means adapted to release the same from the casting before the action of the ejectors on the latter, are shown. Such means consist of forked, open spacing collars 38 adapted to surround the core bolts 40 below the bodies of the cores in position to support the latter in casting position and carried by yokes 39 projecting radially from a shifting ring mounted on the plate 24 and operable circumferentially by means of a handle 40, to carry the collars from under the cores to permit the latter to descend and thus release them from the casting. When the cores descend they bear against blocks 41 carried on the plate 24. These movable cores or their releasing means may be dispensed with if desired.

Mounted in each block 41 are ejector means consisting of a series of vertical pins 42, in line with the die chambers and adapted to be carried against the casting to free it from the dies, when the plate 24 is moved upward. These pins fill openings in the bottom of the die chambers.

Pivottally mounted on the lower ends of bolts 43 extending through the cover 26 are swinging spacer bars 43' adapted to be projected between the upper ends of the contact rods 25 and the bottom of the cover 26, so that when the contact lifting rods are drawn downwardly the bars may be interposed be-

tween the same and the cover in order that in the lifting movement of the plate the cover may be raised before the ejector pins are carried into contact with the casting. These spacer bars are of a greater thickness than the height of that portion of the die chamber which is within the cover member so that the castings may be elevated without contact with the cover after the latter has been raised. The ejectors are withdrawn by lowering the spider and carrier plate.

The operation of the machine is as follows:—

The cover member is placed upon the die bed and locked thereto by means of the bolt 33, and then the sleeve having been raised to the proper point relatively to the die bed 32 is gaged by the contact of the rods 25 against the cover and locked in position by means of the clamping sleeve 12, thereupon the driving bolt is shifted so as to connect the driving mechanism of the shaft 3 with the power means whereupon the shaft and the members 24, 32 and 26 will be rotated at a high rate of speed. The molten metal is then poured into the chamber 34 through the central opening 29 and will be immediately distributed by the centrifugal force to the die chambers through the gates 35. The course of flow of the metal through these gates is, as before described, at an inclination toward the direction of flow and then directly in the line of flow as the metal enters the die chamber, whereby the centrifugal force and the direction of rotation aid in distributing the metal in a continuous even flow with no tendency to back up within the chamber or the gate. The rotation of the machine is continued until the casting is completely formed, whereupon the power is cut off and the brake 9 applied for the purpose of checking the momentum of the shaft and to bring the machine to a quick stop. The bolt 33 is then released from engagement with the die bed 32. When the cores 37 are used the first step in removing the casting is to release these cores from the castings which is done by shifting the ring carrying the yokes 39 so as to carry the spacing collars 38 from beneath the cores 37, whereupon the latter are permitted to descend below the die chamber and rest upon the blocks on the plate 24. The clamp sleeve 12 is then unlocked and the handle 17 with the pinion 16 rotated so as to operate the rack bar 15 and lower the plate 24 relatively to the bed 32 and cover 26 whereby sufficient space is obtained between the upper ends of the contact shifting rods 25 and the bottom of the cover to permit the spacer bars 43' to be swung by hand over between the ends of the rods and the cover. Then the sleeve 11 and plate 24 are again elevated in which movement the contact lifting rods will first strike 130

against the spacer bars 43', thus lifting the cover 26 from the die bed 32 and releasing said cover from the casting and raising it a greater height than the height of the portion of the casting within said cover. In the continued upward movement of the plate 24 the ejectors 42 will enter the die chamber and be carried against the casting, thus releasing it from the die and elevating it slightly so that it may be readily removed. The cover 26 is then removed from the bed and the castings formed in the dies and the gate portions taken out. The plate 24 is then again lowered, so as to withdraw the ejectors and then adjusted in height relatively to the die bed and cover and locked in position and the machine is ready for another operation.

Having thus described my invention, what I claim is:

1. In a centrifugal die casting machine, a die member, a rotatable shaft on which said die member is fixed for rotation therewith, a cover member, means for fixing the cover member to the die member, a third member on the shaft and vertically movable thereon, means for raising and lowering said last named member, and means intermediate the same and the cover member for raising the latter by the upward movement of said vertically movable member after the cover member has been released from the die member.

2. In a centrifugal die casting machine, in combination with a driving shaft, a die member fixed thereon, a cover member, a vertically movable carrier member mounted on said shaft, means for conjointly raising the carrier member and cover relatively to said die member, and for permitting the lowering of the carrier member independently of the cover member.

3. In a centrifugal die casting machine, in combination with a rotatable shaft, a die member carried thereby, a cover member, means to fix the cover member to the die member, a carrier member on the shaft below the die member and movable longitudinally of the shaft, mechanical means for shifting said carrier member, lifting members carried by the carrier member and having contact against the cover member.

4. In a centrifugal die casting machine, in combination with a rotatable shaft, a die member mounted thereon, a cover member, means for rigidly securing the cover member to the die member, a rotatable and vertically movable carrier member mounted on the shaft below the die member, vertical supporting and lifting rods on said carrier having free contact bearing against the bottom of the cover member, manually operated mechanism for raising the carrier and means for locking the carrier in adjusted position.

5. In a centrifugal die casting machine, in

combination with a rotatable shaft, a die bed member fixed thereon, a cover member having dies complementary to those of the die bed, means to removably secure said members together, a carrier plate below the die bed, and mounted for rotation with said shaft and movement longitudinal thereof, vertical lifting rods on said carrier plate having free bearing against the cover member, a non-rotatable, vertically adjustable sleeve on which said carrier plate is mounted, rack and pinion mechanism for raising and lowering said sleeve and means for locking said sleeve in adjusted position.

6. In a centrifugal die casting machine, in combination with a rotatable shaft, separable die carrying members mounted on said shaft, a rotatable and longitudinally movable carrier plate also mounted on the shaft below the die members, mechanism for moving said carrier plate longitudinally, and ejectors carried by said carrier plate and adapted to enter the dies.

7. In a centrifugal die casting machine, in combination with a rotatable shaft, a die bed mounted thereon, a cover member adapted for detachable engagement with said die bed, a rotatable member mounted on the shaft below the die bed for vertical movement relatively to said die bed and cover member, mechanism for raising and lowering said vertically movable member, means carried by said member for lifting the cover from the die bed, and ejectors carried by said member and adapted to enter the dies and operable to release the castings when said member is raised.

8. In a centrifugal die casting machine, in combination with a rotatable shaft, a die bed carried thereby, a cover adapted for detachable engagement with the die bed, a rotatable and vertically movable carrier mounted on said shaft, means carried by said carrier for raising the cover, means carried by said carrier for ejecting the castings and means coöperating with said cover raising means for effecting the lifting of the cover before the ejectors act upon the castings in the upward movement of said carrier.

9. In a centrifugal die casting machine, in combination with a rotatable shaft, die members carried thereby, a vertically movable member, means carried by the movable member for separating said die members, ejectors carried by said movable member, and adjustable means adapted for projection into the path of the separating means to effect the operating contact of said means before the action of the ejectors on the castings.

10. In a centrifugal die casting machine, in combination with a rotatable shaft, a die bed, a die cover member, complementary die elements in said parts, means to detachably

engage said cover with said bed, a vertically 5
slidable and rotatable plate mounted on the
shaft below the die bed, upwardly project-
ing contact rods carried by said plate and
adapted to bear against the under surface of
said cover, ejector pins carried by said plate
and adapted to enter the die recesses, and
movable spacer bars mounted on the die cover
and manually projectable between the bot-
10 tom of the cover and the upper ends of the
lifting rods, and mechanism for elevating
said carrier plate.

11. In a centrifugal die casting machine,
in combination with a rotatable die carry-
15 ing device having a central distributing
chamber, and gates leading from said cham-
ber to the die chambers inclined in the di-
rection of rotation of the machine.

12. In a centrifugal die casting machine,
20 in combination with a rotatable shaft, die
members carried by said shaft and having
a central distributing chamber and gates
leading non-radially and in the general di-
rection of rotation of the machine from said
25 chamber to the die chambers, said gates en-
tering the respective die chambers in the
rear portions of their circumferences con-
sidered with respect to the line of rotation of
the machine.

30 13. In a centrifugal die casting machine,

in combination with a rotatable shaft, die
members carried thereby having a central
open distributing chamber therein, an in-
clined central raised head in said chamber
for aiding the distribution of the metal, and
35 shallow downwardly tapered recesses lead-
ing from the central chamber to the die
chambers and constituting gates, said gates
being wider at their entrance ends than at
40 their exits and extending non-radially from
the central chamber toward the direction of
the line of rotation and entering the die
chambers substantially at the rear thereof in
the line of rotation.

14. In a centrifugal die casting machine, 45
in combination with a rotatable shaft, a die
bed fixed thereon, a movable core adapted to
enter the die, a core supporting plate car-
ried by the shaft below said die bed and a
movable spacer member intermediate said 50
plate and the end of said core.

In witness whereof, I have hereunto set
my hand and seal at Indianapolis this 12th
day of February, A. D. nineteen hundred
and eighteen.
